(57)

CLAIM

The ornamental design for a wrist-worn fluid dispenser, as shown and described.

DESCRIPTION

FIG. 1 illustrates a top perspective view of a wrist-worn fluid dispenser.

FIG. 2 illustrates a bottom perspective view of the wrist-worn fluid dispenser.

FIG. 3 illustrates a front view of the wrist-worn fluid dispenser.

FIG. 4 illustrates a side view of the wrist-worn fluid dispenser; and,

FIG. 5 illustrates a top view of the wrist-worn fluid dispenser.

The broken lines depict portions of the wrist-worn fluid dispenser that form no part of the claimed design.
